HARNESS FOR LOOMS

William J. Samet, Rock Hill, S. C.

Application January 22, 1935, Serial No. 2,935

4 Claims. (Cl. 139—89)

This invention relates broadly to looms and more particularly to a harness therefor.

An object of the invention is to provide a harness of more simple construction than now generally used.

In accordance with the present invention, a harness is provided whereby certain of the rollers and suspension straps required in the old types of harness are eliminated and consequently replacements are less frequent with the harness embodying the features of the present invention.

The invention together with its objects and advantages will be best understood from a study of the following description taken in connection with the accompanying drawings wherein:

Figure 1 is an end elevational view of the loom arch and connected parts of an ordinary loom showing my improved harness therefor.

Figure 2 is a plan view for more clearly illustrating the invention.

Figure 3 is a perspective view illustrating certain features of the invention hereinafter more fully referred to.

Figure 4 is a perspective view of an arm and associated roller embodying the features of the invention, the referred to parts being shown detached; and

Figure 5 is a perspective view of a shoe.

Referring to the drawings by reference numerals it will be seen that in the form of loom illustrated the loom arch indicated by the reference numeral 5 is provided with upwardly extending brackets 6, 7, and journaled on the brackets 35 are the rollers or pulleys 8, 9. A harness frame is indicated by the reference numeral 10.

Heretofore the common practice was to provide on the bracket of the loom corresponding to the bracket 7 cam shaped pulleys one for each harness frame. In accordance with the present invention such pulleys are eliminated and in their stead there is used what may be termed a shoe 11.

The shoe 11 shown in Figure 5 is substantially U-shaped having elongated coextensive arms 12 which straddle the free end of the upwardly extending arm 7a of the bracket 7, the shoe 11 at the closed end of the U being secured to the bracket arm 7a by bolt and nut means or other suitable fastening means 13. Adjacent said free end the bracket arm 7a on the side thereof opposite to the side from which the sides 12 of the shoe 11 project is provided with an abutment or shoulder 14 against which the shoe 11 at the closed end thereof abuts.

By providing a shoe such as the shoe 11 the coil springs 15, in contra-distinction to the usual form of harness, are placed through the medium of the shoe in direct connection with the bracket arm 7a, one end of the coil springs 15 being connected to the arms of the shoe 11 by wire loops or the like 16. For accommodating the loop 16 the sides 12 of the shoe at one edge are suitably notched as at 18 the notches being staggeredly arranged as shown in Figure 5.

There is provided a coil spring 15 for each harness frame, and also for each harness frame there is provided a single flexible suspension cable or strap 19. Each strap 19 is passed through an eye 20 on the free end of the proper spring 15, and the ends of the strap are suitably secured to the top of the harness frame 10 as shown in Figure 1 and indicated at 21. Also, one end portion of the suspension strap 19 is trained over the roller or pulley 8 on the bracket 6, while the other end portion of the suspension strap is trained over the pulley or roller 9 on the bracket 7 all of which will be clear from a study of Figure 1.

From the above it will be apparent that a harness embodying the features of the present invention is of a simple and economical construction.

Having thus described my invention, what I claim as new is:

1. In a loom, the combination with the loom arch and harness frame, of a pair of upwardly extending brackets mounted on the arch, a roller mounted on each bracket, one of said brackets having an upwardly extending arm, a laterally projecting U-shaped shoe on the free end of said arm, a plurality of coil springs, one for each harness frame, loops engaging the shoe and connected with one end of said springs, and a flexible suspension member for each harness frame, each suspension member being threaded through an eye on the free end of one of the coil springs, the ends of the suspension member being connected with the harness frame with the end portions of the suspension member trained over the rollers.

2. As a part of a loom harness a roller supporting bracket provided with an arm, a U-shaped shoe straddling the arm and having the sides thereof provided with notches in one edge, coil springs, their being one coil spring for each harness frame, loops connecting one end of each coil spring with one of the side members of the shoe and engaging a notch in the side member and each coil spring having a free end provided

with an eye and a harness frame suspension element threaded through the eye.

3. A bracket for harness frames having an up-standing arm, a U-shaped member straddling the arm and secured thereto adjacent one end of the arm, said U-shaped member having each side thereof provided at one edge with a series of notches.

4. A bracket for a harness frame and includ-

ing an arm, a U-shaped member straddling the arm and secured at the closed end of the U to the arm, an abutment shoulder on the same side of the arm as the closed end of said U-shaped member and against which said closed end abuts, and said U-shaped member having each side thereof provided for connection with one end of a coil spring forming part of the harness. 5

WILLIAM J. SAMET.
